UNITED STATES PATENT OFFICE

FRANK G. CARRINGTON, OF ANNISTON, ALABAMA, ASSIGNOR TO FERRIC ENGINEERING COMPANY, OF ANNISTON, ALABAMA, A CORPORATION OF DELAWARE

COOLING SYSTEM

Application filed March 23, 1927. Serial No. 177,652.

This invention relates to a cooling system, and more particularly to a cooling system in a centrifugal casting apparatus where it is desired to progressively cool the mold.

5 While my invention may be employed in any of the methods for casting by a centrifugal process, it is particularly adapted for use in the so-called "end-pouring trough process". In this process, metal is poured from 10 the end of a trough over which a rotating mold telescopes, whereby the molten metal is built up in spirally related columns on the interior of the mold.

Difficulty has been experienced in effecting 15 a proper cooling of the mold, and as a result the operative lives of the molds have been shortened, and there have been certain deleterious effects in the cast objects, principally brittleness, which has necessitated an annealing 20 process for the casting. There have been various cooling systems devised to take care of this situation, most of which have consisted in surrounding the mold with a water jacket. Others have provided pipes for 25 sprinkling the mold with a cooling medium.

In all the systems heretofore employed, however, the cooling has been commenced along the length of the mold at the same moment. The metal, however, is poured 30 from the end of a trough which moves axially with respect to the mold, so that there is an interval between the pouring at the two ends of the mold. Inasmuch as the cooling is commenced at the same time, metal is 35 poured on successive portions of the mold which have been cooled for different periods of time, and which portions therefore are of different temperatures. This means that a casting is subjected to different cooling 40 along its length, especially with reference to initial cooling upon coming into contact with the mold.

Inasmuch as the cooling effect on the mold is transferred to the poured metal, this variance 45 in the cooling of the mold makes for a longitudinal differential in the cooling of the metal—in other words, the metal poured at the spigot end of the mold is cooled more rapidly than at the bell end. As the texture 50 of a casting is a function of its cooling, the

spigot end of the pipe will be of a different texture from the bell end.

Moreover, quite regardless of the deleterious effects upon the casting resulting from the employment of former cooling systems, 55 in the mold itself there have been set up uneven stresses, and in practice it has been found that the mold fails at the spigot end.

Many of the cooling systems heretofore employed have also necessitated a subsequent annealing process. There have been no means adapted for a gradual cooling of the mold, and necessarily of the molten metal, but, on the contrary, the cooling has been so sudden 60 that the cast pipes have been case chilled. Annealing has been necessary to render such 65 case chilled pipes usable.

The problem is, therefore, one of cooling the mold so that it is capable of functioning 70 over a series of castings, and at the same time preventing the too rapid cooling, and consequent case chilling, of the poured metal. To accomplish this is one of the objects of this invention.

Another object of this invention is to devise 75 a method of cooling a mold.

Still another object of this invention is to devise a method of progressively cooling a mold in a centrifugal casting apparatus.

Yet another object of this invention is to provide 80 a cooling system for a mold.

A further object of this invention is to provide 85 a system for cooling a rotary mold at a predetermined relationship to the deposition of molten metal within the mold.

A still further object is to provide a cooling system whereby the mold in a centrifugal casting apparatus may be cooled progressively and at variant rates along its length.

Yet a further object of this invention is to provide 90 a cooling system for a centrifugal casting mold whereby the mold is subjected to the cooling action only as metal is deposited therein.

To accomplish the above, and other important objects as will more fully appear hereinafter, my invention, in general, comprises cooling members and means for operating the individual cooling members so 95 that additional increments of the mold are 100

cooled, or so that a section of the mold, which progresses its length, is cooled.

To insure a more accurate comprehension of my invention, but in no way limiting myself to the particular apparatus and details therein set forth, reference is made to the accompanying drawings, in which similar numerals indicate corresponding parts.

Figure 1 is a top plan view of the complete invention;

Fig. 2 is a side elevational view of the apparatus with a portion of the mold cut away;

Fig. 3 is a cross sectional view along the line 3—3 of Fig. 1, looking in the direction of the arrows;

Fig. 4 is a cross sectional view of one of the sectional pipes along the line 4—4 of Fig. 3, looking in the direction of the arrows;

Fig. 5 is a detailed view of the truck arm shown in Figs. 1 and 2;

Fig. 6 is a top view of a ladle truck and valves by the operation of which a mold is cooled in a section which progresses longitudinally of the mold;

Fig. 7 is a detailed view of the valve partially in section, along the line 7—7 of Fig. 6;

Fig. 8 is a sectional view of the valve on the line 8—8 of Fig. 7;

Fig. 9 is a top elevational view of a valve, being a modification of the valves shown in Fig. 6, whereby the cooling effected by a section is terminated by stages;

Fig. 10 is an adaptation of the invention, in which molten metal is deposited before the cooling commences;

Fig. 11 is another adaptation in which cooling of the mold precedes the deposition of metal.

Referring more particularly to Fig. 1, a casting mold 1 having a bell end 2 and a spigot end 3, is mounted upon trunnions 4 supported on roller boxes 5. The mold is rotated by mechanical means, not shown in the drawings, the rotation generating the centrifugal force necessary to disperse the metal over the interior surface of the mold.

Standards 6 are spaced along the length of the mold and mounted thereupon are blocks 7. Cooling sections comprising independent pipes 8 closed at both ends, extend longitudinally of the mold and are supported in the blocks 7. These pipes have apertures to disperse a cooling medium upon the mold. Each group of pipes is independent of the groups in the other sections of the system, but the pipes of each group are connected to a supply pipe for that group by the feed pipes 9.

Valves 10 are mounted in the system, as indicated, to cut off or regulate near the standards the supply of cooling medium into any desired section. Adjustment of these valves enables a different cooling effect along the length of the pipe to be obtained. This is of considerable value for it is frequently

necessary to increase the cooling of the bell end, because of the greater deposition of metal there, for instance.

The medium is conveyed to the dispersing pipes by the independent supply pipes 11 and 11' on which are mounted near their junction with a conduit 12 valves 13, 15, and 16. These valves have levers 14 for opening or closing the passages. Any desired section therefore may be operated and controlled by the valves 13. It will be observed that the valves are regularly spaced, except for the two first valves 15 and 16, which are in closer proximity, the reason therefor appearing hereinafter.

An end pouring trough 17, for conveying molten metal from a ladle 18 to that place in the mold where it is desired to deposit the metal, is mounted on a truck 19, which also carries the ladle. This truck is provided with wheels 20 for running upon a track 21. A finger rod 22 is attached to the truck by means of bolts or other fastening means. This rod may either be of angular formation, extending outwardly and downwardly from the truck, or it may be mounted obliquely to the side of the truck. These alternative formations are for the purpose of so placing the finger rod that its end will be capable of contact with the levers 14 of the valves 13, 15 and 16, opening the valves when passing along the track to the right. In order that this finger rod may be raised so that the truck may pass along the track 21 without coming into contact with the levers, a hinge 23 is provided so that the lower portion of the finger may be raised.

At the commencement of a pouring operation, the truck is placed at the end of the track adjacent the mold and during the process is moved to the right by mechanical means, not shown. During this passage the finger comes into progressive contact with the levers 14, opening the valves and consequently bringing into play successive sections of the cooling system. At the termination of the casting operation the entire series of sections will be dispersing a cooling medium upon the exterior of the mold, and when it is desired to remove the cast pipe the valves 13, 15 and 16 may be closed manually, or by suitable mechanical means.

In Fig. 2 there is a more detailed illustration of the relation between the pouring of the molten metal and the operation of the cooling system. In the bell end of the mold there is fixed a head core 25 which serves to form a channel into which the metal may flow, thus shaping the bell of the pipe. When the operation is started, the truck is advanced to the left until the spout or end 26 of the trough is at approximately 27. The valve 15, admitting the fluid to the leftmost section is opened before or at the same time the pouring is commenced. Inasmuch as a greater thickness is

required at the bell end of the pipe than at the barrel of the pipe, the trough remains substantially stationary at 27 for a short time. When a sufficient amount of metal has been deposited, the truck begins its movement to the right, and in the process the finger rod opens the valve 16 when the spout of the trough reaches 28. This causes the next section to disperse the medium upon the mold. 5 And so, in succession, as the trough reaches a point in the mold corresponding to the beginning of a new cooling section, the valve for that section is opened. 10

Fig. 2 also sets forth a base 29 on which the mold and major portion of the cooling system is supported. It will be noted that the track 21 is on a somewhat lower plane, although this is not necessary. The supply pipes 11 and 11', conduit 12, and valves are 15 below the track 21, which necessitates the angle formation of the finger rod 23.

In Fig. 3, a cross sectional view of the mold and cooling apparatus, the staggered alignment of the dispersing pipes 8 is shown. This 20 can be compensated for, however, by so arranging the apertures in the pipe that the stream of the medium is directed on the mold at any desired place. As before stated, the ends of the pipes 8 are closed as at 30. This 25 figure also shows the arcuate shape of the supply pipes 11, and the standards 6.

The apertures 31 in the pipes 8 are regularly spaced as shown in Fig. 4, although under certain conditions other arrangements may be 30 made. The mounting of the pipes 8 in the blocks 7 is of such a nature as to preclude a loosening or slipping of the pipes in respect to the mold, and the ends 30 of the pipes are set flush with the far side of the block 7.

40 The finger rod 22 is provided with a hinge 23, through which a bolt, or other suitable pivot 32, as shown in Fig. 5, extends. This enables an operator to raise the lower portion 22' when returning the truck to the starting 45 position. If the valve is incapable of movement counter-clockwise, and the hinge is easily operated, it is unnecessary to manually raise the lower part of the rod 22', for upon coming into contact with the lever 14, the 50 lower part will swing upward.

The complete invention is designed to provide a method of progressively cooling a mold by extending the cooling area in stages as the metal is deposited therein, the progression 55 being consistent with the deposition of the metal stream. While this is not a steady progression but one wherein increments are added, by shortening the sections the sectional effect will be so slight as to be negligible. But 60 regardless of the length of the sections, all that portion of the mold is cooled which has upon its interior surface a hot mass of metal, and the cooling is not effected until practically the moment at which the metal is poured.

65 It will be noted that the commencement of

the sprinkling within an increment is simultaneous throughout that increment, and in this respect the apparatus which is the subject of this invention, differs from the cooling system covered by my copending application Serial No. 172,355, filed March 3, 1927. 70

All the foregoing refers to a cooling system in which, at the moment pouring ceases, the entire mold is being cooled. When the left-most section is once put in operation it continues until the termination of the complete process. This means that the different sections are subjected to different periods of cooling, the bell end, for instance, being cooled for a longer period than the spigot, or plain, end. Usually this variation is immaterial, for the cooling is of vital importance only when metal is within the critical range of temperature. The resulting microstructure of the metal is dependent upon the speed 80 at which the metal passes through this range. Above and below the critical temperatures the metal may be cooled rapidly or slowly without any appreciable effect upon its structure. 85

90 The system heretofore described is designed to avoid a sudden and rapid cooling of the metal within the critical range. As stated, however, there does remain a differential cooling between the spigot and bell ends of the pipe. 95

100 It may therefore, under certain circumstances, be desirable to provide a cooling system, by the operation of which each portion of the mold is subjected to the same amount of cooling as every other portion, particularly with reference to the length of time it is cooled. This is accomplished by providing a system in which a sectional cooling is effected. The cooling section, of any desired length, progresses longitudinally of the mold. This 105 means that, as the section progresses, any given point on the mold is cooled for the same length of time as every other point, provided the number of cooling units in a progressive section remains constant, and that there is no acceleration in the speed at which the section travels. 110

115 This progression, as in the case of incremental cooling heretofore described, accomplished by the apparatus shown in Figures 1 and 2, may be in any desired relationship to the pouring of the metal. It is also to be noted that the progression of this section is by stages, the stages being determined by the length of the sectional cooling members 120 or units. The cooling is commenced simultaneously throughout the length of each stage.

I have shown in Figures 6 to 11 inclusive an apparatus for accomplishing this type of cooling. Certain modifications are embodied 125 in the various types illustrated in the figures.

In Figure 6 there is shown the trough 17, the ladle 18, mounted on the truck 19, the supply pipes 11 and 11' and the conduit 12, all as shown in the preceding figures. 130

The finger rod 22 is shown mounted on the truck, its exact position however being changed from that occupied in Figs. 1 and 2. As will appear hereafter, the position of this arm is immaterial, provided it is in a proper spaced relationship to an arm 33 which is shown in Figure 6. Both of these arms are provided with hinges 23 as heretofore described.

Secured to the pipes 11' and 34, which latter pipe is joined to the conduit 12, is a valve.

Referring to Figs. 7 and 8, this valve comprises a casing 35 which is screw-threaded to the pipes 11' and 34, as at 36. Threaded upon this casing is a cap 37 having a central aperture therein. A valve stem 38 passes through this aperture and is secured to the valve 39, shown in this drawing as of the mushroom type. The valve rests within the valve seat 41, and is held in fluid-tight contact therewith by means of a helical spring 42, the upper portion of which presses against the cap 37. The valve is provided with a channel 43, of the same size and shape as the channels 44 of the valve seat and 45 of the casing.

When in alignment with the two last mentioned channels the valve channel permits the passage of water from the pipe 34 to the pipe 11'. This valve may be rotated within the seat and its channel turned as indicated by the dotted lines 46 in Fig. 8. When in this last position the valve affords a water-tight obstruction in the path of the channels 44 and 45 of the valve seat and casing. It will be observed that to insure this obstruction to the flow of water, it is necessary to rotate the valve 90°.

Upon the upper portion of the valve stem 38 there is affixed a spindle 47 secured to the stem by means of a bolt 48, or other suitable fastening means, in order to prevent rotation of the spindle with respect to the stem. The spindle supports four lever arms 49, at right angles to each other.

The finger rods 22 and 33 in passing the valves, turn the valve levers through an arc of 90°. This in turn effects a rotation of the valve 39, and closes the flow of water if the valve is open. If, on the other hand, the valve is closed, the finger rod 22 opens the valve.

As the truck moves from left to right, and assuming that all of the valves are closed, the finger 22 opens the valves in succession.

As the truck continues its movement to the right, the finger 33 turns levers 49 through another 90°, closing the valves. The operation therefore is one of opening the valves by the finger 22, letting the cooling units remain in operation for a determined period, and then closing the valves by the finger 33. This process is synchronized to the pouring of metal within the mold.

The spaced relationship of the fingers 22 and 33, and the speed at which the truck

moves, determine the length of time any given cooling section is in operation. Variations, therefore, in the distance of the two fingers may be made in order to accomplish any desired result for a particular casting 70

It will be noted that the valves are closed rapidly and the cooling by any section terminated abruptly. It is sometimes desirable to stop the cooling gradually, and to accomplish this I have shown in Figure 9 a modification of the valve employed.

The valve casing, seat, and valve stem may be of same type as that shown in Figures 7 and 8. Instead of having only four levers, 80 however, there are provided twelve levers or spokes 51, mounted upon the spindle 47.

The arm 22 is provided for opening the valves, but there are three arms 52, instead of only one, for closing the valves. The arm 22 is of a length to contact with the spokes at a point on their radii, where a rotation of 90° may be effected. As above pointed out, this is a sufficient movement of rotation to open a closed valve. The arms 52, however, are shorter, and move the spokes through an arc of only 30 degrees. This reduces the flow of the cooling medium through the valve by one third, and the sum of the rotation effected by the three arms 52 is sufficient to 90 totally close the valve.

Various modifications may be made of this arrangement to vary the termination of the cooling. The farther apart the arms 52 are spaced, the more gradual will be the termination of the cooling. It may be desirable under certain circumstances to employ only one arm 52, reducing the cooling effect one third at some determined time and then allowing the cooling to continue thus diminished. For instance, after the temperature of the casting has dropped below the critical ranges, it may be desirable to decrease, yet not terminate altogether, the cooling of the mold. Another modification may embrace an apparatus in which the positions of the arms 22 and 52 are transposed, so that the cooling is gradually commenced but suddenly terminated. Or again, a plurality of arms 52 may be employed to both gradually commence and gradually terminate the cooling.

In Figure 2 there is shown a synchronization of the cooling and pouring in which the two operations are practically concomitant. This is usually the preferred method, but under certain circumstances it may be desirable to have the cooling precede, or, under other circumstances, to follow the pouring. While the cooling in Figure 2 is incremental, it can readily be seen how this concomitant cooling might easily be effected in the case of a cooling by a progressive section. In Figure 10 I have shown a portion of a mold and cooling apparatus in which a progressive section follows the pouring of the metal. In this par- 110 120 125 130

ticular figure the cooling succeeds the pouring at a distance of approximately one cooling unit. This distance may be varied, either increasing or diminishing the distance, and consequently the time, between the pouring and cooling. Under such an arrangement, the metal is poured in a mold of substantially atmospheric temperature, and after the metal is cooled for a certain period, independent of artificial cooling, the apparatus increases the rapidity of the cooling. This might be especially desirable, for instance, where a metal is poured at a temperature within, or just above, its critical range. In this way it would pass through the range at a slow rate, and then the artificial cooling would expedite its reduction to a temperature at which it might be removed from the mold. As pointed out hereinbefore, it is of prime importance that a metal pass through its critical range of temperature at a controlled speed, for the cooling within that range determines certain properties of the finished casting simultaneously with deposition of metal in the mold.

In Figure 11 the cooling precedes the deposition of metal. Here again the precedence is by one cooling unit, which as above stated, may be varied with different operations. When the cooling precedes the deposition of metal the mold is considerably reduced in temperature by the time metal is poured in it. Under some circumstances this may be found desirable. It may be that where a metal is poured at a considerably higher temperature than its critical range, this method would expedite the drop in temperature of the metal to the critical range, and from thence onward the metal cools unaided by artificial means.

In the foregoing I have shown certain modifications of my invention. It is to be understood that the same general principles underlie all applications of my invention. The relationship of the cooling and the pouring applies with equal force, whether it be an incremental cooling or a cooling in a progressive section. Under certain conditions of operation it may be extremely desirable to insure that when metal is poured that portion of the mold receiving the metal is of the same temperature as every other portion of the mold at the moment metal is poured, and especially that every particle of metal passes through its critical range at a uniform speed, regardless of the position in the mold that such a particle is deposited. My apparatuses and processes can be so operated as to accomplish this and other desirable results.

My invention insures a slower and more gradual cooling than is the case with the cooling systems heretofore employed. The cooling effect of the latter has been so acute and rapid as to cause a case chilling of the cast pipe, and in order to render such a pipe

usable, it is necessary to subject it to an annealing process whereby the outer surface is softened to an extent where it is possible to employ it in ordinary operations. The obviation of such a costly and time consuming step as annealing by this invention will facilitate the rapid and more effective casting of metal pipe.

Where I have used the term "pipe" in the specification and claims, it is to be understood as covering a casting of any description produced by the centrifugal process. It is also to be understood that the word "iron" is not to limit the use of my invention to the production of ferrous castings. My invention may be employed to cast articles composed of any material.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. A system for cooling a mold in a centrifugal casting process comprising a series of independent pipe sections adapted to be individually operated, and means to operate the sections in a determined relationship to each other, the said means being synchronized with the deposition of metal in the mold.

2. A sectional cooling system comprising a series of pipes extending longitudinally of a mold, apertures in the pipes for dispersing a cooling medium on a rotating mold, independent valves for regulating each section, and means to successively operate the valves.

3. A rotary casting apparatus comprising a revolvable mold, supported longitudinally thereabove independent sections of a cooling system, feed lines for the sections having valves therein, a pouring trough capable of longitudinal movement with respect to the mold, and means associated with the pouring trough for opening in succession the said valves.

4. A rotary casting apparatus comprising a rotatable mold, supported thereabove and extending substantially the length of the mold a series of independent sections of paired pipes for discharging a cooling fluid upon the exterior of the mold, an independent feed line, with valve mounted thereon, for each section, a trough extending within the mold and adapted to be withdrawn while molten metal is poured therefrom, a ladling device attached to the trough and capable of movement as the trough is withdrawn from the mold, and means on the ladling device for opening the above mentioned valves.

5. A rotary mold cooling system comprising individual cooling sections, means for commencing and terminating the operation of the individual sections and other means synchronized with the deposition of metal in the mold for actuating the first mentioned means.
10. A centrifugal casting apparatus comprising a rotatable mold, a trough adapted to move axially with respect to the mold, a sectional cooling system, individual valves for admitting a cooling medium to the sections, and means coacting with the trough for opening and closing the valves.
15. A centrifugal casting apparatus comprising a mold mounted for rotation, a ladling device, the mold and ladling device relatively movable with respect to each other, a plurality of independent pipes mounted adjacent the mold and adapted to disperse a cooling fluid thereon, means for regulating the admission of a cooling fluid to the several pipes, and means carried by the ladle for actuating the last mentioned means in a definite relation to the deposition of metal within the mold.
20. In testimony whereof I affix my signature.
FRANK G. CARRINGTON.
